UNITED STATES PATENT OFFICE.

JOHN F. UPTON, OF SAPULPA, OKLAHOMA.

VALVE FOR AIR STARTER SYSTEMS.

1,313,767.

Specification of Letters Patent.

Patented Aug. 19, 1919.

Application filed April 29, 1919. Serial No. 293,467.

To all whom it may concern:

Be it known that I, JOHN F. UPTON, a citizen of the United States, residing at Sapulpa, in the county of Creek and State of Oklahoma, have invented certain new and useful Improvements in Valves for Air Starter Systems, of which the following is a specification.

This invention relates to improvements in pneumatic starter systems for explosive engines and has for its primary object to provide an improved valve structure for controlling the admission of compressed air to the engine cylinder.

Another object is the provision of valve actuating means by which the valve may be manually opened for a brief period to admit sufficient air to the cylinder to carry the crank shaft of the engine for a half revolution.

Another object is the provision of a valve structure of this character in which the valve is automatically returned to closed position subsequent to an operation thereof to automatically cut off the supply of air to the engine cylinder.

With these and other objects in view as will appear as the description proceeds the invention comprises the novel features of construction, accompanied by elements and arrangement of parts which will be more fully described in the following specification and set forth with particularity in the claims appended hereto.

Figure 1 represents a fragmental side elevation of a conventional type of explosive engine illustrating the invention applied to use.

Fig. 2 represents a longitudinal sectional view through the valve, partly broken away, and,

Fig. 3 represents a detail elevation of the controlling device for the valve.

Referring to the drawing in detail, where-
in similar reference characters designate corresponding parts throughout the several views the numeral 5 indicates a substantially T-shaped valve casing the head portion 6 of which is formed with aligned inlet and outlet ports 7 and 8, respectively, the former being

adapted to receive an air supply pipe 9 adapted for connection with a reservoir in which is stored compressed air under adequate pressure to actuate the piston therein and impart an initial rotary movement to the crank shaft.

The stem 10 of the valve casing is formed throughout a portion of its bore with internal screw threads receiving a plug 11 constituting a guide for the valve stem 12 and the terminal of the plug is formed with a recess disposed concentric with the bore and receiving a preferred type of packing element 13 held in place by cap nut 14 to prevent leakage of air about the stem. The inner terminal of the stem is pivotally secured at 15 between integral bifurcations 16 carried by a slide valve 17 which latter is movable over the plane face or seat 18 formed by one side of a vertical partition 19 formed internally of the head 6 and adjacent the outlet port 8. An expansion spring 20 is confined between the plug 11 and a collar or ring 21 secured to or formed integral with the stem 12 and the tension of which normally tends to elevate and close the valve 17 over the diagonal port 22 through the seat or partition 19.

The outlet terminal of the port 8 is formed with exterior screw threads 23 whereby the valve casing is secured in the head of an explosive engine cylinder 24, as suggested in Fig. 1, and is provided internally with threads receiving a sleeve 25 provided with internal side arms 26 supporting a guide 27 in which is slidably mounted the stem 28 of the valve 29. A nut 30 is fitted upon the terminal of the stem 28 and constitutes an abutment for one terminal of a spring 31 the opposite end of which is engaged by the guide 27 and normally retains the valve 29 in engagement with its seat 32 provided at the beveled edge of the sleeve 25.

A disk 33 is mounted upon a support 34 attached to the base of the engine 24 and is provided with a substantially semicircular flange 35 one terminal of which is beveled as at 36 for engagement with the pivoted latch 37. A laterally projecting pin 38 is formed upon the disk 33 at a point adja-

cent the beveled terminal of the flange 35 and is engageable behind the beak or finger 39 of the latch 37 and the latter is provided at its upper terminal with bifurcations receiving a pin 40 detachably engaged in the hooked terminal 41 of the valve stem 12 whereby the latch and valve stem are pivotally and detachably coupled together. In order that the length of the latch member 37 may be varied to adapt the device to various types of engines, the latch is separately constructed in two sections connected by a screw 42.

In applying the invention to use the outlet terminal of the head 6 is secured in the head of the explosive engine cylinder 24 in such manner that the interior of the sleeve 25, when the valve 29 is open, communicates with the explosion chamber and air fed to the interior of the valve casing through the supply pipe 9 is normally prevented from entering the explosion chamber by the valve 17. During operation of the engine, the valve 29 acts in the manner of a check valve preventing the burning gases from entering the interior of the air valve and the tension of the spring 31 is preferably such as to prevent the valve 29 from being automatically opened by the suction or partial vacuum created within the engine cylinder during the intake stroke of the piston. However, under abnormal conditions as when the engine is permitted to operate at a high speed with the throttle valve partially closed, the excessive reduction of pressure in the engine cylinder may effect the valve 29 but air is prevented from crossing the port 29 by the valve 17.

In operation, and assuming that it is desired to start the engine 24, the disk 33 is turned to the position shown in Fig. 3, the pin 38 effecting downward movement of the latch 37, stem 12 and valve 17 thus uncovering the port 22 and permitting the air to enter the interior of the cylinder through the sleeve 25, the pressure of the air acting upon the rear face of the valve 29 automatically opening the latter against the tension of the spring 31. As the turning movement of the disk 33 is continued beyond a predetermined point, the shoulder 36 is brought into engagement with the adjacent edge of the latch section 37 and, acting in the manner of a cam, displaces the latch member laterally of the disk 33 and disengages the pin 38 from the finger 39 thus releasing the latch and valve stem and permitting the valve to return to its closed position under the influence of the spring 20. By thus providing for the automatic release of the valve the latter is maintained in open position for a comparatively brief period but sufficient to admit the proper quantity of compressed air to the combustion chamber of the engine

which, acting upon the piston, forces the latter outwardly and imparts a rotary movement to the crank shaft. Subsequent to an operation of the valve, the disk 33 is restored to its initial position and the latch 37 engaged with the pin 38. Should a single operation of the starter fail to set the engine 24 in operation, the valve may be actuated as many times as is necessary in order to obtain the desired result.

What I claim is:

1. A valve for engine starters including a housing having inlet and outlet ports, a valve arranged in the housing and controlling the passage of fluid between the ports, a stem carried by the valve, means for normally retaining the valve in closed position, means connected with the stem for opening the valve, and means for automatically disengaging the stem from the opening means during the opening movement of the valve. 75

2. A valve for engine starters including a housing having inlet and outlet ports therein, a valve controlling the passage of fluid between the ports, a stem connected with the valve, means connected with the stem for actuating the valve, and means for automatically disengaging the stem from the actuating means during the opening movement of the valve. 80

3. A valve for engine starters including a housing having inlet and outlet ports therein, an apertured partition arranged between the ports and constituting a valve seat, a slide valve movable over said seat, a stem carried by the valve, means arranged internally of the housing normally tending to close the valve, said housing having a hollow extension communication with the outlet port adapted for connection with the cylinder of an explosive engine, an inwardly closing check valve arranged in the terminal of the outlet port, and means arranged internally of the housing normally retaining the last mentioned valve in closed position. 95

4. A valve for engine starters including a housing, a valve mounted therein, a stem carried by the valve, a rotatable member, a pin carried thereby, means carried by the stem detachably engaged with the pin for imparting movement of the rotatable member to the valve. 100

5. A valve for engine starters including a housing having inlet and outlet ports therein, a valve controlling the passage of fluid between the ports, a stem carried by the valve, a rotatable member, a pin carried by said member, a hook carried by the stem engageable with the pin, and means carried by the rotatable member for automatically disengaging the hook of the stem from the rotatable member during the opening movement of the valve. 115

6. A valve for engine starters including a

housing, a valve supported therein, a stem carried by the valve, a hook pivotally connected with the stem, a rotatable member, a pin carried by the rotatable member engageable with the hook whereby movement of the 5 rotatable member is transmitted to the valve, and a shoulder carried by the rotatable

member engageable with the hook for disengaging the latter from the pin and releasing the valve.

10

In testimony whereof, I affix my signature hereto.

JOHN F. UPTON.
